JIGSAW PUZZLE ASSEMBLY BOARD

Lois A. Noyes, Van Nuys, Calif., assignor to Springbok Editions, Inc., New York, N.Y., a corporation of New York

Filed Nov. 14, 1966, Ser. No. 4,638

Term of patent 14 years

(Cl. D34—5)

The single figure is a plan view of a jigsaw puzzle assembly board showing my new design.

The broken lines in the drawing are actual markings on the board.

The jigsaw puzzle assembly board of my new design is of conventional thickness.

I claim:

The ornamental design for a jigsaw puzzle assembly board, as shown and described.
